WRAPPING OF CIGARETTES AND OTHER ARTICLES

George Daniel Horgan, London, England, assignor to American Machine & Foundry Company, New York, N. Y., a corporation of New Jersey

Application March 6, 1937, Serial No. 129,370
In Great Britain April 8, 1936

6 Claims. (Cl. 229—51)

This invention relates to the wrapping of cigarettes and other articles of the type comprising an outer covering of transparent or translucent material in which the packet of cigarettes or the like is enclosed and which may form a moisture proof covering.

These outer wrappings may consist of material such as that known under the registered trademark "Cellophane" or "glacine," and as these wrappings are sealed as by heat-sealing or by the use of an adhesive in order to facilitate the removal tearing tabs are provided. Such tabs are usually arranged in the middle of one of the broad faces of the packet adjacent an end thereof and it is found that the tear caused by pulling the tab normally develops into a V-shape and frequently terminates in the face of the wrapper on which the tab is formed so that further tearing is necessary before the wrapper may be finally removed.

An object of the invention is to provide an improved wrapping which will permit an easier opening and removal of the wrapping.

A further object is to provide a wrapping blank having tabs and adapted to be severed from a strip or web without waste.

Further objects will appear hereinafter.

According to the invention a wrapping for a packet of cigarettes or other like articles is provided with one or a pair of tearing tabs located to cause a tearing of the wrapper along one (or both) narrow sides of the packet.

The invention also comprises a wrapper, preferably severed from a strip or web, having one or a pair of tearing tabs located adjacent the longitudinal edges of the strip.

The invention also comprises a wrapped packet having one or a pair of tearing or opening tabs located at the narrow sides of the packet.

Further features of the invention will be hereinafter described and defined in the claims.

The accompanying drawing illustrates a blank wrapper according to the preferred form in Figure 1, while

Figures 2 to 5 show various stages in applying and folding the wrapper upon a carton.

Figure 6 shows the completed wrapped carton.

It is to be noted that Figures 2 to 6 are illustrative only and are not to be taken as setting out definite steps in the folding as such will be obvious to those versed in the wrapping art and may be readily carried out by the aid of known appliances.

In carrying the invention into effect, as applied by way of example to the wrapping of car-

tons of cigarettes in transparent coverings such as "Cellophane" or like material, the wrapper 10 is formed with two tearing tabs 11, 12 which project from a transverse edge 13 of the wrapper and are located adjacent the longitudinal edges 14, 15 of the wrapper.

The lateral dimensions of the tabs are preferably such that the terminus of each of their inner edges 11a, 12a, when the wrapper is applied, coincide with edges of the carton.

In cutting the wrappers it is preferred to sever them from a web or strip so that the other transverse edge 16 of the wrapper is complementary to the edge having the pair of tabs, i. e., the edge 16 will comprise a long central tab and stepped back corners whereby there will be no waste of material. If desired, however, the edge 16 in question may be cut square without the long central tab as the latter is unnecessary so far as the improved wrapping is concerned. By 20 the illustrative showing of the transverse margin 16 as straight, it is not intended to exclude the provision of a blank with an edge of curved or other suitable contour.

The longitudinal dimensions of the wrapper 25 are such that when it is applied to the carton 17 the transverse margin having the long central tab 16 (or no tab) will fold over the longitudinal edge of the carton and partially down the face panel 17 thereof as seen in Figure 2 so that 30 when the other transverse margin having the tabs 11 and 12 is brought upwardly its edge 13 will coincide or be slightly set back from the aforesaid longitudinal edge, and so that the tabs 11 and 12 will project beyond such edge, as seen 35 in Figure 3. The overlapping longitudinal margins of the wrapper 15a, 15b, 15c, 15d (Figure 3) are then folded down onto the narrow faces of the carton in known manner, for example by first folding the overlaps 15c and 15d, then the 40 overlap 15b, the overlap 15a having the tearing or opening tab preferably being folded last so that it lies uppermost.

The transverse dimension of the wrapper may be such that the overlap 15a extends to the edge 45 of the carton or is set back therefrom as seen in Figure 6.

The corresponding overlapping margins at the other end of the carton are similarly folded down.

Sealing of the overlapping parts is effected in 50 any suitable way as by heat-sealing or by a suitable adhesive.

The wrapped packet will thus have been provided with a pair of tearing or opening tabs 11 and 12 associated with the two longitudinal

narrow faces of the carton and projecting beyond the corner edges of the packet.

On pulling either of the tabs it will be found that the wrapper will be torn along the continuous edge of the packet leaving the remainder of the wrapper so vulnerable that it may be readily removed.

Obviously only a single tab may be provided.

While the invention has been particularly described in connection with the "Cellophane" wrapping of packets of cigarettes it will be obvious that any article of a like shape may be provided with the improved wrapping according to the invention. Moreover, the wrappers may be formed of any other transparent or translucent material.

According to the preferred arrangement the tabs, in severing the wrapper from a web, are formed by three transverse cuts joined by a pair of longitudinal cuts which latter are preferably inclined, thus providing squared tabs. The tabs may, however, be of any other desired shape; thus they may be of rounded outline.

Further, the tabs may be provided with a starting cut adjacent the corners 11a, 12a, particularly in tougher wrapping materials.

I claim:

1. An enwrapped package of the class described; said package comprising a cigarette carton or like packet of substantially rectangular contour having front and rear face panels, sides, and ends, defined by substantially straight lengthwise edges and straight transverse edges intersecting the longitudinal edges at right angles; and a wrapper comprising a sheet of somewhat tough wrapping material, such as "Cellophane"; said sheet including in a single substantially continuous member material sufficient in area to extend completely around two face panels and the intervening sides of said packet; with marginal material extending over each end of the packet and folded and sealed in overlapping arrangement; at least one of said end margins being provided with a tab free from sealing attachment to the underlying folds and constituting an extension of an entire end of said wrapper, so that upon retroverting said tab and pulling it manually the associated end fold structure can be ruptured and removed, leaving the remainder of the wrapper vulnerable for ready complete removal from the packet.

2. An enwrapped package of the class described; said package comprising a cigarette carton or like packet of substantially rectangular contour having front and rear face panels, sides and ends, defined by substantially straight lengthwise edges and straight transverse edges intersecting the longitudinal edges at right angles; and a wrapper comprising a sheet of transparent sheet material such as "Cellophane", having a tear-resisting characteristic; said sheet including in a single substantially continuous member material sufficient in area to extend completely around two face panels and the intervening sides of said packet; with marginal material extending over each end of the packet and folded and sealed in overlapping arrangement; at least one of said end margins being pro-

vided with a tab free from sealing attachment to the underlying folds and constituting an extension of an entire end of said wrapper, so that upon retroverting said tab and pulling it manually the associated end fold structure can be ruptured and removed, leaving the remainder of the wrapper vulnerable for ready complete removal from the packet.

3. An enwrapped package of the class described having the features claimed in claim 1, in which said tabs is aligned with a transverse end edge of said wrapper, so that upon retroverting said tab and pulling it manually along the entire length of said transverse end the entire associated end fold structure can be ruptured and removed, leaving the remainder of the wrapper vulnerable for ready complete removal from the packet.

4. An enwrapped package of the class described; said package comprising a cigarette carton or like packet of substantially rectangular contour having front and rear face panels, sides and ends, defined by substantially straight lengthwise edges and straight transverse edges intersecting the longitudinal edges at right angles; and a wrapper comprising a sheet of transparent sheet material such as "Cellophane", having a tear-resisting characteristic; said sheet including in a single substantially continuous member material sufficient in area to extend completely around two face panels and the intervening sides of said packet; with marginal material extending over each end of the packet and folded and sealed in overlapping arrangement; each of said end margins being provided with a tab free from sealing attachment to the underlying folds and constituting an extension of an entire end of said wrapper; so that upon retroverting said tabs and pulling them manually the end fold structure of the wrapper can be ruptured and removed from both ends, leaving the intermediate body portion of the wrapper vulnerable for ready complete removal from the packet.

5. A wrapper blank for a cigarette carton or like packet having the features claimed in claim 1, in which provision is made of a tearing tab projecting beyond a transverse edge of the blank and adjacent to a longitudinal edge thereof; said tearing tab being defined by an edge perpendicular to said longitudinal edge of the blank, and merging into said transverse edge of the blank by a shoulder inclined at an obtuse angle to the last-named edge at their meeting point.

6. A wrapper blank for a cigarette carton or like packet having the features claimed in claim 1, in which provision is made of a pair of tearing tabs projecting beyond a transverse edge of the blank and adjacent to the longitudinal edges thereof, each of said tabs being defined by an edge parallel with that of said other tab and by an edge perpendicular to said longitudinal edges of the blank, and each tab merging into the transverse edge by a shoulder inclined at an obtuse angle to said transverse edge of the blank, whereby the initial tearing point of each tab is localized while unintended tearing is resisted.

GEORGE DANIEL HORGAN.
